DISTRIBUTOR HEAD FOR STOKERS

Andrew M. Hunt, Berkeley, Calif.; Crocker First Federal Trust Company, executor of said Andrew M. Hunt, deceased, assignor to The Standard Stoker Company, Incorporated, a corporation of Delaware

Application November 11, 1930, Serial No. 494,829

3 Claims. (Cl. 110—101)

This invention relates to stokers of the scatter feed type, and more particularly to that type wherein the fuel is introduced through an opening in the rear wall of the firebox and there projected over the fire by means of jets of pressure fluid.

It is an object of the invention to provide, in a distributing mechanism of stokers of the type described, a novel sectional distributor head having that portion thereof in which the jet openings are formed or the hood portion as a separable member from the main body of the distributor head.

Another object of the invention is the provision of a new and improved distributor head that is cheap to manufacture, simple in construction, and one in which the hood portion may be readily and easily removed or replaced for purposes of repair or removing clogs.

Other and further objects and advantages of the invention will appear from the following description taken in connection with the accompanying drawings, in which

Fig. 1 is a vertical central section of a portion of a locomotive and a stoker therefor, showing the invention in position therein;

Fig. 2 is a plan section on line 2—2 of Fig. 1;

Fig. 3 is an isometric view of the lower or main body section of the distributor head;

Fig. 4 is an isometric view of the upper or hood section of the distributor head;

Fig. 5 is a section on the line 5—5 of Fig. 1;

Fig. 6 is a central vertical longitudinal section through a portion of a locomotive, showing a modified form of the invention in place; and

Fig. 7 is a plan view on the line 7—7 of Fig. 6.

Referring now to the drawings, the reference character 10 designates a locomotive having the backhead 11 provided with the firedoor opening 12. The structure thus far described may be of the usual or any well known construction, and further description or illustration is unnecessary.

A suitable stoker 13 is provided for supplying fuel to the locomotive. The stoker comprises a riser conduit 14 which constitutes the forward section of a series of conduits leading from a suitable source of fuel supply such as a locomotive tender. The riser conduit 14 extends upwardly and is curved forwardly for delivering the fuel to the opening 12 onto a distributor plate 15, and is provided with a movable cover section 16 hinged at its upper end as at 17 and held in closed position by the latch 18, whereby access may be had to the interior of the riser conduit.

The distributor plate may be of any type suit-

able for spreading fuel over the firebox, that shown in the figures being the preferred form. The plate 15 is detachably secured at its rearward face to the upright wall 19 of the conduit 14 and forms an extended floor portion therefor. The forward side portions of the plate 15 are provided with the pockets 20, 20a, and the J-shaped deflecting ribs 21, 21a, which serve to receive and direct a portion of the fuel to the rear corners of the firebox.

Rearwardly of the distributor plate 15 and vertically disposed in the upright wall 19 of the conduit 14 is the plate-like distributor head 22 arranged to receive pressure fluid such as steam. The distributor head 22 is provided with a plurality of steam chambers 23, from the upper end of each of which jet openings 24 in horizontal alignment are adapted to direct blasts of pressure fluid across the upper surface of the plate 15 for forcing the fuel to all parts of the firebox 20 as rapidly as it is delivered onto the plate 15. Each chamber 23 is provided with a separate pipe 25 for supplying steam thereto.

My invention contemplates the use of a novel distributor head comprising a main body or lower portion 26 and a separable hood or upper portion 27. It frequently happens that the jet openings become clogged and it is usual to remove the clogs by inserting a piece of wire into the jet openings. Some of the dirt and clogging matter will be forced into the chambers 23, and in time it is necessary to entirely remove the distributor head and disconnect the steam supply pipe 25 in order to remove the accumulation of dirt and dust in the chambers of the distributor head. This is a troublesome and time consuming job causing inconvenience and delay. In my improved distributor head construction the body portion of the distributor head and steam supply pipes are not at all disturbed and dirt can be conveniently and quickly removed from the steam chambers by removing the easily accessible hood portion of the distributor head and blowing out the dirt by means of the blast from the steam supply pipes 25.

The steam issuing from the jets 24 will also in time cut or wear away the sides of the jet opening and in prior constructions it has been necessary to remove and replace the entire distributor head. My invention necessitates the replacement only of the hood or upper portion of the distributor head, saving time, trouble and money and making repairs and replacements possible without disarranging or disturbing any part of 55

the distributor or stoking mechanism except the hood portion of the distributor head.

The main body or lower portion 26 of the distributor head 22 is securely attached to the conduit 14 by headed screws 28, 28a through its attaching arms or lugs 29, 29a extending laterally from the upright side walls of the distributor head. The hood or upper portion 27 of the distributor head is securely attached to the conduit 14 by headed screws 30, 30a through its attaching arms or lugs 31, 31a extending laterally from the upright side walls of the distributor head. The hood portion 27 and the main body portion 26 of the distributor head are fitted together so that their upright side walls exactly register, and are securely and tightly attached to each other by the headed screws 32, 32a through the drilled holes 33, 33a and the tapped openings 34, 34a of the registering chamber walls 35, 35a and 36, 36a, respectively. A soft copper or other suitable gasket 37 is placed between the contacting surfaces of the hood and main body portions of the distributor head to insure a tight connection therebetween.

The main body or lower portion of the distributor head extends upwardly a distance slightly above the floor of the conduit 14 to permit easy removal and replacement of the hood portion and to permit proper adjustment and tightening thereof. The extension of the main body of the distributor head above the floor of the conduit also prevents particles of coal and coal dust from being swept into the chambers 23 during removal or replacement of the hood portion of the distributor head.

Figs. 6 and 7 illustrate a modified form of the invention wherein the distributor head is provided with a hood 38 having a lip 39 formed integral therewith and extending forwardly therefrom. The lip 39 has a tendency to flatten the blast of pressure fluid issuing from the jet openings 24 and cooperates therewith to form a flat fan-shaped pressure fluid blast. This construction reduces the arc of the aerial path of the fuel and reduces the amount of fuel ordinarily escaping over the firebox arch unconsumed. Fuel delivered through the riser conduit 14 is urged across the lip 39 and is dropped onto the distributor plate 15 somewhat in advance of the jet openings 24, thereby minimizing clogging of the openings which occurs from time to time when the fuel is permitted to drop onto the distributor plate immediately in front of the jet openings.

I claim:

1. In a stoker, a fuel distributor plate, a conduit for delivering solid fuel to said distributor plate having a substantially horizontal discharge mouth portion, a sectional pressure fluid distributor head, comprising a plate-like body portion and a hood portion, said body portion being inserted in the floor of the horizontal mouth portion rearward of said distributor plate and said

hood portion surmounting said body portion and extending above the top surface of the floor of said horizontal mouth portion, said hood portion having a row of jet openings extending transversely of said conduit mouth portion and arranged to issue pressure fluid blasts over the top surface of said plate, and a lip formed with and extending forwardly from said hood portion immediately above and extending beyond said jet openings and overlying said distributor plate.

2. As a new article of manufacture, a discharge section of a sectional pressure fluid distributor head comprising a flat front face, a flat base substantially at right angles thereto, an arcuate roof joining the remote edges of said front face and said base, said discharge section in cross section perpendicular to said base and front face being approximately quarter round, said discharge section being provided with passages extending upwardly through said base and terminating short of said arcuate roof, the front face of said discharge section having a row of discharge orifices disposed at approximate right angles to said passages, each opening at one end into one of said passages and a lip formed with and extending forwardly at substantially a right angle from the front face of said discharge section immediately above and substantially parallel with said row of orifices.

3. In a stoker, a fuel distributor plate, a conduit for delivering fuel thereto having a substantially horizontal mouth portion, a sectional pressure fluid distributor head comprising a pressure fluid receiving section and a pressure fluid discharge section, said receiving section being inserted in the floor of said horizontal mouth portion and being provided with partition walls to form a plurality of passages therein open at their respective opposite ends, said discharge section surmounting said receiving section and extending above the top surface of the floor of said mouth portion, said discharge section being provided with partition walls to form a plurality of passages therein, said first named walls and passages registering with said second named walls and passages to form continuous passages and walls in said receiving and said discharge sections, said discharge section having a plurality of spaced horizontally aligned jet openings therein communicating with the passages in said discharge section for issuing pressure fluid blasts across the top surface of said plate, certain of the partition walls of said receiving section having threaded openings therein, the partition walls of said discharge section having openings extending therethrough and registering with said threaded openings, and means extending through the openings in the partition walls of said discharge section arranged to securely fasten said discharge section to said receiving section.

ANDREW M. HUNT.
